UNITED STATES PATENT OFFICE

MARTIN FISCHER, OF ZURICH, SWITZERLAND

PNEUMATIC CLOCK SYSTEM

Application filed March 19, 1927, Serial No. 176,692, and in Switzerland March 21, 1926.

My invention relates to a central clock construction or system comprising a main clock including means adapted to produce, in predetermined intervals or intermittently, a vacuum or a pressure in a system of more or less distributed or branched conduits for the purpose of operating or synchronizing suitably constructed conjugate or subordinate clocks through the differences in pressure resulting therefrom.

In the accompanying drawings forming a part of this specification I have shown, for purposes of exemplification, two preferred embodiments of the essential and novel parts of the clocks, but for clearness sake I have omitted therefrom all those parts and mechanisms of the clocks which are of conventional construction and arrangement and, therefore, are known to those skilled in the art to which this invention relates.

Referring to the drawings:

Figure 1 is a diagrammatic side view, partly in section, showing the pneumatic operating details of a clock construction or system.

Fig. 2 is a side view, partly in section, showing a crank mechanism in place of the lever mechanism of the piston of Fig. 1.

Fig. 3 is a diagrammatic side view of a releasing mechanism,

Fig. 4a is a side view of a portion of the arbor,

Fig. 4b is a side view of the arbor of Fig. 4a in a different position,

Fig. 4c is a similar view in a still different position, and

Fig. 5 is a side view, partly in section, of the mechanism of a conjugate clock.

The main clock is provided and co-operates with a pneumatic cylinder 7, see Figure 1, with a piston 6 fitting therein, a driving rod 3 being pivotally connected to the piston 6.

The toothed wheels 4 and 5 of the clock are mounted to permanently engage with each other, the wheel 4 having a square head on its shaft, being the driving wheel adapted to be actuated by the operating mechanism of the clock (not shown) so that the two wheels will rotate at the same time in the directions indicated by the arrows in Figure 1.

Fixedly mounted in the wheels 4 and 5 are a number of pins 25 which are located in certain predetermined positions so as to co-operate with a three-armed lever 1 pivotally fulcrumed at 2, during each revolution of the wheels 4 and 5. One arm of the lever 1 is pivotally connected with the piston rod 3 and it will be seen that while a pin 25 of the wheel 5 engages a lower free arm of the lever 1 and causes the same to move downwards, a corresponding pin 25 of the wheel 4 will subsequently act to lift the other free arm of the lever so that the continued revolutions of the wheels 4 and 5 will cause, through the agency of the lever and the rod 3, the piston 6 to incessantly reciprocate in vertical direction.

The piston 6 acts in the manner of a counterweight with relation to the two free lever arms. If required a proportionate auxiliary weight may be attached to the lever in any suitable manner for balancing purposes in order to obtain impellant forces—pressure and suction—of the same value at the raising and the lowering movements of the piston 6.

In the modification illustrated in Figure 2 a crank mechanism is substituted for the lever mechanism shown in Figure 1. In this embodiment the clockwork is adapted to engage with or operate the crank 10 for the purpose of reciprocating the piston 6' in the cylinder 7' by means of the rod.

In Figures 3 and 4a, 4b and 4c, I have shown a mechanism suitable for releasing the described time actuating mechanism through the clockwork. The toothed wheel 4' which, as above described, co-operates with the wheel 5 to actuate the three-armed lever 1, is caused to revolve constantly in the direction indicated by an arrow in Figure 3. Adjacent to the wheel 4' a yielding bell-crank lever 12 is mounted to oscillate about a pivot 11.

The wheel 4', see Figure 3, is equipped with six pins or studs 25 symmetrically arranged in diametrical relationship and adapted to engage the short arm of the bell-crank lever 12 during the revolution of the wheel 4' in order to raise the said arm from the position shown in full lines to that illustrated in dotted lines. The star wheel 14 of

the clockwork controlled by an oscillator 15, is keyed to an arbor 13, having in its outwardly projecting end a cut or steep thread, as will be seen in Figures 4a, 4b and 4c.

5 The wheel 14 possesses thirty teeth and is controlled by a second-pendulum to form the second-wheel.

The drive for the wheels 4, 5 and 14 is carried out either by means of a weight or a 10 spring in the direction of the arrows for wheels 4 and 5 and for the second-wheel 14 in the direction of the clock hand. The drawings show a weight 27 for driving the wheel 5 and a weight 27' for driving the wheel 14. The wheels 4 and 5 are driven by the driving means and not from the clock-work.

When the clock is going the arbor 13 and the star-wheel thereon will revolve and at 20 the same time the wheel 4' of the clockwork is caused to revolve in the direction of the arrow, due to the action of the usual driving spring, weight or the like. During the revolution of the wheel 4' any of the six pins will engage the shorter arm of the bell-crank lever 12 and lift the same so that the longer or upright arm of the lever 12 will come in contact with the arbor 13. After a 25 certain length of time the contacting extremity of the lever 12 engages in the thread, as shown in Figure 4a, and owing to its resiliency, moves laterally in the thread towards the free end of the arbor so as to finally disengage from the arbor, as will be readily understood upon inspection of Figs. 4a, 4b and 4c while the arbor is constantly rotating and continues to rotate after the lever 12 has disengaged and has been caused subsequently, by the pressure exerted by the engaging pin 40 of the wheel 4', to adopt the position shown in dotted lines in Figure 3.

On the continued movement of the wheels 4' and 5 the piston 6 is operated, as hereinbefore described, and thereafter the lever 12 is caused by the action of a restoring spring 26 to return to its position shown in full lines in Figure 3. In doing so the free extremity of the lever reengages the thread of the arbor, but of course from the opposite side, and is again ejected therefrom in the manner above described.

In the meantime the pin which has engaged the shorter arm of the lever 12, has moved to be out of the way of the returning lever arm and the latter, therefore, engages the next pin in order to again lock the wheel 4' which thus is stopped and not released until the upright arm of the lever again disengages from the arbor 13, as hereinbefore described.

50 It will be seen that in this manner the release is efficiently and accurately controlled by the slow-rotating thread or oblique cut in the free end of the arbor 13.

65 The rotation of the wheels 4 and 5 will be slowed up by means of the pins 25 in such

a way that as soon as the lever 12 is released from the thread oblique cut of the arbor 13, the spring 26 will pull the lever down so that it will again contact with a pin 25. Also the lever has contacted against the arbor 13, which will result in arresting the rotation of the wheels 4 and 5.

70 In Figure 5 I have shown the mechanism of a conjugate clock according to the present invention. The vacuum or the pressure produced by the piston 6 in the cylinder 7 of Figure 1, is conveyed through a suitable conduit such as 8, see Figure 1, and 24, see Figure 5, to a cylinder 23. In case of a vacuum the piston 22 will be moved towards the top of the cylinder and the rod connecting the piston with a lever 20, will act to raise the lever and in case of a pressure the piston 22 will be driven towards the open end of the cylinder and act to lower the lever 20. The latter is fulcrumed on a stationary pin 18 and provided with a pin or pawl 19 near the meeting point of the two intermeshing wheels 16 and 17, which possess each thirty circumferential teeth of triangular shape.

75 It will be seen that the lever 20 is reciprocated by the up and down movements of the piston 22 so that the pawl alternately engages the wheel 16 and the wheel 17 in order to feed the same for one sixtieth or one minute. The minute-hand of the conjugate clock is, as indicated in Figure 5, positively connected with the wheel 16 in any appropriate manner. For balancing purposes the lever 20 is counterweighted by means of a 80 weight 21 supported by the free end of the same. When the piston 6 of the main clock is drawn out or away from the bottom of the cylinder 7 the piston of the conjugate clock will carry out at the same time a movement 85 in opposite direction, that is, towards the top of the cylinder 23, and the return movement of the piston 6 causes the piston 22 to also return at the same time.

90 The pneumatic clock constructions for synchronizing a plurality of clocks as hitherto constructed or suggested are usually provided with air conduits of a comparatively large cross-sectional area for the purpose of 95 reducing thereby the resistance of conduction. This is objectionable, however, for the reason that the high elasticity of the air in tubular systems of a large cross-section involves a high degree of resiliency or cushioning resulting in considerable losses of energy.

100 After much study and research I have found that it is possible and of advantage to employ narrow pipes or tubes in the pneumatic transmitting system and to use, especially in the branch conduits, pipes or tubing of an extremely small cross-sectional area. In most cases a conduit having an internal diameter of about 1 to 4 mm. will give highly satisfactory results, so that, for 105 instance, in a pneumatic transmitting system

of a total length of about 600 m. The air contained therein will amount to 3 to 4 litres only, whereby resiliency and loss of energy are minimized. The retardations occurring 5 in the conjugate clocks which are farthest remote from the main clock, amount, at the highest, to a few seconds only and are practically negligible. If it is desired, however, to remedy this unessential defect, throttling 10 means may be employed. Thus by inserting capillary pipes into the conduits of the conjugate clocks which are least remote from the main clock the retarding effect will be greatly reduced and a noiseless running of the 15 conjugate clocks will be obtained thereby.

It will be evident that my invention, whilst still being adhered to in its main essentials, may be varied and adapted in many ways, according to requirements desired or most 20 suitable under different circumstances. I have not attempted to explain all of the minute details of the constructions and arrangement of the several clocks and the pneumatic synchronizing system controlling the 25 same, for it will be understood by those to whom this specification is addressed, that the parts will necessarily be of the proper size and relationship and properly arranged to suit the purposes in view.

30 It seems unnecessary to reiterate the operation of the entire clock arrangement or system for the operation of the essential parts embodying the invention has been described in detail. Nor does it seem necessary to burden this specification with an exposition of 35 the advantages which the invention possesses for they will be apparent to persons versed in the art.

What I claim is:—

40 1. A pneumatic clock system including a main clock comprising a cylinder; a piston in said cylinder; a three-armed lever having one arm pivotally connected with said piston; two intermeshing toothed wheels forming 45 a part of the clockwork; and a series of pins arranged on each wheel to alternately engage the second and third arms of the lever to cause a pressure and partial vacuum in the cylinder by the piston.

50 2. A pneumatic clock system according to claim 1 comprising a star wheel for the clock-work; and a bell crank lever having one arm cooperating with the pins of one of the wheels and the other arm in communication 55 with an arbor of the star wheel of the clock-work to provide a periodic operation of the three-armed lever and the piston.

In testimony whereof I affix my signature.
MARTIN FISCHER.
